UNITED STATES PATENT OFFICE

103,248

DESIGN FOR A VEHICLE

Alexis R. Pribil, Saginaw, Mich.

Application February 21, 1936, Serial No. 61,283

Term of patent 7 years

To all whom it may concern:

Be it known that I, Alexis R. Pribil, a citizen of the United States, residing at Saginaw, in the county of Saginaw and State of Michigan, have invented a certain new, original, and ornamental Design for a Vehicle, of which the following is a specification, reference being had to the accompanying drawing, forming a part thereof.

In the drawing—

Fig. 1 is a side elevational view of a vehicle showing my new design.

Fig. 2 is a top plan view; and

Fig. 3 is a front elevational view.

What I claim is:

The ornamental design for a vehicle as shown.

ALEXIS R. PRIBIL.
